JOSEPH FRANCOIS BRUN AND PAUL ALBERT BRUN, OF NEW YORK, N. Y.

WATCH BEARING.

Application filed June 5, 1924. Serial No. 718,002.

To all whom it may concern:

Be it known that we, JOSEPH FRANCOIS BRUN and PAUL ALBERT BRUN, citizens of Switzerland, and residents of the borough of 5 Manhattan, in the city and State of New York, have invented new and useful Watch Bearings, of which the following is a specification.

This invention relates to watch construction and, more particularly, to that portion of the watch which serves as a bearing for the balance staff or pivot.

An object of the invention is to provide means for permitting the cap jewel which 10 acts as an end or thrust bearing for the balance staff or pivot to move axially within its immediate confining element so as to allow for a corresponding movement of the balance staff or pivot when the watch is subjected to a sudden blow or jar, thereby obviating, to a great extent, breaking or bending of said balance staff or pivot.

Another object consists in providing means for performing the function just 15 stated, which means can be applied to any watch of ordinary or standard construction without necessitating alteration of the balance bridge.

A further object consists in providing 20 certain improvements in the form, construction and arrangement of the several parts, whereby the above named and other objects may be effectively attained.

A practical embodiment of our invention 25 is represented in the accompanying drawings, in which—

Fig. 1 represents a detail top plan view of 30 that portion of a watch mechanism designed to embody the invention.

Fig. 2 represents a section taken in the 35 plane of the line II—II of Fig. 1, looking in the direction of the arrows; certain parts being shown in different positions in full and dotted lines.

The balance bridge of the watch is denoted by 1 and within it is fixed a jewel 2 which is bored, as indicated at 3, to provide 40 a journal for the end of the balance staff or pivot 4.

This jewel 2 may conveniently be fixed in 45 place by upsetting the surrounding edges of the bridge 1, above and below the jewel 2, as indicated, for instance, at 5.

On the upper part of the bridge 1 there is 50 located a suitable plate 6, which may be removably secured to the bridge by means of

screws 7, 8 that pass through holes 9, 10 in the bridge and are threaded into holes 11, 12 in the plate 6.

The said plate 6 has a central opening 13 60 which is axially coincident with the opening in the bridge 1 in which the jewel 2 is confined, and a cap jewel 14 is set in said opening 13 so as to rest upon one face of the jewel 2 and abut the end of the balance staff 65 or pivot 4.

The upper wall of the aperture 13 is flared outwardly and upwardly, as indicated at 15, and a concave disk spring 16, composed of sheet metal or other suitable material, is 70 fitted to rest on said flared surface 15, and is held in place by upsetting the surrounding upper edge of the plate 6 as indicated, for example, at 17.

The said spring 16 has a central aperture 75 18 which is fitted to receive the central portion of the convex upper end of the cap jewel 14, as indicated at 19.

The tension of the spring 16 is normally downward so that it yieldingly urges the 80 cap jewel 14 against the end of the balance staff or pivot 4 and against the upper surface of the jewel 2.

It will be observed that there is a slight 85 allowance for side motion or play of the cap jewel 14 within the opening 13, but the aperture 18 in the spring 16 cooperates with the convex upper end of the cap jewel 14 to normally hold the latter centrally within the opening 13.

Thus, the arrangement is such that the 90 function of the spring is to normally and simultaneously hold the cap jewel in its lowermost and central position; but it is important to note that the surrounding wall of 95 the opening 13 positively prevents any substantial lateral movement of the cap jewel away from its central position.

In operation, when the watch receives 100 any shock which places a strain upon the balance staff or pivot 4, the same may yield in a longitudinal direction by forcing the cap jewel upwardly against the tension of the spring, as indicated in dotted lines in Fig. 2. This capacity for yielding tends 105 greatly to prevent bending or breaking of the balance staff or pivot; and, as soon as the force of the blow or jar is spent, the spring will force the cap jewel and balance staff or pivot back to normal position.

From the foregoing description, it will 110 be seen that our invention may be applied

to any ordinary watch works, without the necessity of altering the construction thereof, since it is only requisite to screw the plate 6 to the bridge 1. The plate 6 carries all the operating parts.

It will be understood that various changes may be resorted to in the form, construction and arrangement of the several parts without departing from the spirit and scope 10 of our invention; and hence, we do not intend to be limited to the details herein shown and described, except as they may be included in the claims.

What we claim is:—

16. 1. Apparatus of the character described comprising, an operating pivot, a cap jewel engaging the end of said pivot, a housing immediately surrounding the cap jewel, and a spring fixed against bodily movement in 20 said housing and normally urging the cap jewel against the pivot, whereby the cap jewel is permitted to yield axially in its housing under pressure exerted by said pivot.
20. 2. Apparatus of the character described comprising, an operating pivot, a cap jewel engaging the end of said pivot, a housing surrounding the cap jewel, and a circular spring carried by said housing and normally urging the cap jewel against the pivot, whereby the cap jewel is permitted to yield axially in its housing under pressure exerted by said pivot, said spring having a central

aperture and said cap jewel having a convex upper end directly mating with said aperture, whereby the cap jewel is normally held in axial alignment with said pivot. 35

3. Apparatus of the character described comprising, an operating pivot, a cap jewel engaging the end of said pivot, a housing surrounding the cap jewel with a space between the two, and a circular spring carried by said housing and normally urging the cap jewel against the pivot, whereby the cap jewel is permitted to yield laterally in 45 its housing under pressure exerted by said pivot, said spring having a central aperture and said cap jewel having a convex upper end directly mating with said aperture, whereby the cap jewel is normally held in 50 axial alignment with said pivot.

4. Apparatus of the character described comprising, a bridge, a bearing jewel fixed in said bridge, an operating pivot journaled in said jewel, a plate attached to the top of the bridge, a bare cap jewel loosely housed in said plate so as to abut the bearing jewel and the end of said pivot, and a spring carried by said plate and directly abutting the upper end of said cap jewel. 55

In testimony, that we claim the foregoing as our joint invention, we have signed our names this third day of June 1924.

JOSEPH FRANCOIS BRUN.
PAUL ALBERT BRUN.
